UNITED STATES PATENT OFFICE.

LESTER E. VAN HISE, OF ALTADENA, CALIFORNIA, ASSIGNOR TO JAMES V. BALDWIN,
OF LOS ANGELES, CALIFORNIA.

INTERNAL-COMBUSTION ENGINE.

Application filed May 12, 1925. Serial No. 29,823.

This application is a continuation in part of application Serial No. 498,434, filed September 3, 1921.

The invention in this case relates to internal combustion engines, particularly to the fuel feed mechanism thereof.

An object of the invention is to provide a novel, simple, and effective apparatus which will be automatic in operation and will require practically no attention to maintain it operative.

Another object is to provide a fuel feeding apparatus in which the amount of fuel fed to the engine thereby is in direct proportion to the engine speed.

A further and most important object is to eliminate the objectionable feeding of unvaporized fuel directly to the intake or to the lubricating mechanism which is necessarily inherent in those fuel feeding devices of the prior art in which the fuel feed depends upon suction exerted through a conductor connecting a vacuum tank and the engine intake, or a vacuum tank and the oil pump mechanism of internal combustion engines. My invention does not include a vacuum tank, nor anything else by which fuel can be fed to or reach any part of the engine except through the carburetor thereof. The invention comprises an unbroken conductor the interior of which communicates with the main fuel tank and the carburetor only, thereby eliminating the slightest chance of oil dilution which is the inevitable concomitant of prior devices of the type mentioned.

A further object is to utilize the energy ordinarily wasted and remaining in the fuel after its passage through the engine to cause the continuous operation of the fuel feeding mechanism.

Other objects will become apparent as the detailed description proceeds.

In the drawings:

Figure 1 illustrates an automobile incorporating the improved fuel elevating and feeding means.

Figure 2 is a fragmentary cross sectional view showing the fuel elevating and feeding means as a whole.

Figure 3 is a fragmentary sectional view showing a modification of part of the fuel feeding means.

Figs. 4, 5 and 6 are sectional views showing other modified forms of the invention.

The fuel feed mechanism A of the motor vehicle B is used to feed fuel to an auxiliary tank C, the vehicle B comprising the usual internal combustion engine 1, exhaust duct 2, carburetor 3, main fuel supply tank 4, and feed line 5 leading from said tank 4.

The mechanism A includes a valve member a, which comprises a housing 6 provided with valve chambers 7 and 8 having a connecting port 9. A valve seat member 10 is detachably connected to one end of housing 6 and has a ball valve 11 yieldingly held to the seat therein by a spring 12, a flanged member 13 being used to secure the feed line 5 to the housing 6.

The chamber 8 has a ball valve 14 normally held to its valve seat by the spring 15 to close the port 9, a port 16 being provided to establish communication between the chamber 8 and the pipe 17 suitably connected to the housing of chamber 8 by the member 18 as shown in Figure 1.

The pump b comprises a shell of bottle 19 having a part thereof inserted in the exhaust duct 2, and held therein by the screw 20 projecting from the bottom of shell 19 through the duct 2 and a nut 21 threaded on the screw 20. The shell 19 and housing 6 are provided with aligned openings to form a port 22 communicating with port 9, and a valved priming device 23 is provided for the purpose of introducing priming fuel to the mechanism.

The pipe 17 establishes communication between the port 16 and the auxiliary tank C in which is arranged, as an overflow, the projecting end of the return pipe 24 leading back to the main storage tank 4. A pipe 25 leads from the bottom of the auxiliary tank C to the carburetor 3.

In the modification shown in Figure 3, the pump bottle 26 is designed for insertion vertically in the exhaust duct 2, and for this reason is of different construction from that shown in Figure 2. It comprises the outer shell 26 having an inner shell 27, of smaller external diameter than the internal diameter of the shell 26, secured concentrically therein with the closed end 28 spaced slightly from the bottom 29 of shell 26. The inner shell 27 is provided with ports 30 to establish communication between the annular space 31 between the two shells and the chamber 32 of shell 27. The chamber 32 is connected directly to the pipe 5 by means of

the short pipe 33, the pipe 17 of the device shown in Fig. 2 being eliminated by this construction. Check valves similar to those shown in Figure 2, but not shown in Fig. 3, are arranged in the line 5 on opposite sides of the short connecting pipe 33 to serve the same purpose as those shown in Figure 2.

To start the apparatus, it is necessary to provide the carburetor with sufficient fuel to start the engine and keep it in operation for a short time. This initial charge for the carburetor is obtained from the auxiliary tank C which may be filled for this purpose with fuel through the plug 33. The pumping mechanism A is filled with fuel through the primer 23, and needs no priming after the first, as there is always sufficient fuel left in the auxiliary tank and the pumping mechanism to start the engine and set the pumping mechanism in operation.

After initial priming as just described, or after such use as leaves the apparatus primed, the starting and continued operation of the engine causes the exhaust gases to heat the pump shell inserted in the exhaust duct. This heat applied to the shell expands the fuel with which it was primed, and partly vaporizes it, with the result that some of the fuel is forced past the check valve nearest the auxiliary tank C; the check valve nearest the main supply tank preventing any fuel being forced backward thereto. These valves are not reversely acting; they must act in the same direction. The valve nearest the supply tank is not actually necessary, and in practise is usually omitted. When a column of liquid fuel is forced past one of the valves to the auxiliary tank C, its inertia continues to move it toward the said tank and creates a vacuum behind it, even after the pressure in the bottle has been relieved which causes fuel to be forced by atmospheric pressure from the main tank past the nearest check valve into the bottle and the spaces communicating therewith between the two valves. This alternate expulsion and reception of fuel by the pumping bottle continues as long as there is fuel in the main tank and heat is applied to the bottle. The fuel is forced from the pumping bottle to the auxiliary tank in alternate strata of liquid and vapor which causes a continuous pulsating feed of liquid fuel to the auxiliary tank from which the fuel is fed by gravity to the carburetor.

In Figure 4, a very compact and efficient modification of my invention is shown. Here, the outer pump shell 35 is fixedly positioned by any suitable means in the exhaust 36, and has an inner shell 37 fixed to the bottom closure 38 and extending upwardly therein with its outer surface concentric with and spaced apart slightly from the inner surface of the outer shell 35. The top of

the inner shell 37 is closed by a plug 39, and series of apertures 40 are provided therein adjacent its bottom near the closure 38.

The upper end of shell 35 is provided with a closure 41 having an aperture 42 in which is seated the end 43 of a cooling coil fuel conductor 44, enclosed in the auxiliary supply tank 45. The shell 35 has a valve seat member 46 secured therein adjacent the closure 41 to form a valve chamber 47 in which is seated a plate valve 48 shaped substantially as shown in Figure 6. This plate 48 has a central portion 49 which closes the aperture 50 in said member when in contact with seat 51. The projections 52 on the plate 48 keep it centered in shell 35 and provide the spaces 53 (shown in dotted outline) which permit fuel to pass around the central portion 49, when the plate 48 is lifted from its seat, to the entrance end 43 of coil 44.

Between the valve member 46 and the top 39 of the inner shell, the outer shell 35 is provided with an aperture 54 which communicates with a passageway 55 extending from the base 56 of the auxiliary tank 45. The passageway 55 is connected by pipe 5' to the main fuel supply tank 4 to conduct fuel therefrom into the space between valve 46 and the top 39 of the inner shell of the pump.

An overflow pipe 57 extends upwardly from base 56 and is connected by a return line 24' to supply tank 4. The usual vent 58 is provided at the upper part of the tank 45, and a pipe 25' connects the lower part of the base 56 with the carburetor.

In the modification just described, the cool incoming gas flowing on top of and around the inner shell 37 reduces the temperature thereof very quickly—after its heating during a fuel expulsion period—and serves to keep within the necessary operative limits the ratios of lengths of vapor strata to the lengths of liquid fuel forced into the auxiliary tank.

In Figure 5, there is shown a modification in which the outer pump shell 35 is provided with a nozzle 59 to increase the velocity of expulsion of the fuel from the pump to the auxiliary tank. A jacket 60 surrounds the greater part of the shell 35 which projects from the exhaust, and has a pipe 5" connecting its lower end to the supply tank 4. Apertures 61 in shell 35, adjacent to the entrance end of pipe 5" admit fuel into the space between the two shells of the pump. The upper end of the jacket 60 is provided with valve mechanism similar to that shown in Figure 6, and has a pipe 17" extending therefrom to an auxiliary supply tank similar to that shown in either Figures 3 or 6.

In the modification shown in Figure 6, the outer shell 35 is provided with a cooling jacket 61 from the top of which a pipe 62 leads to the auxiliary tank 63. The pump

proper is identical with that shown in Figure 4, and has connected thereto a pipe 5" leading from the supply tank 4. A pipe 64 connects the valve chamber at the top of shell 35 with the bottom of jacket 61. Particular attention is directed to the fact that the pipe 5" feeds directly into the shell 35 and not into the jacket 61 as it does in the modification shown in Figure 5, and that all fuel expelled from the pump must pass through the pipe 64 and the cooling jacket 61 before it can reach pipe 62 leading to the auxiliary tank 63. This arrangement condenses and reduces the lengths of the vapor strata and keeps the temperature of the apparatus within operative limits.

I claim:—

1. The combination with the exhaust duct of an internal combustion engine, of a pumping bottle having a part thereof seated within said duct, pipes extending in opposite directions from said bottle, and communicating with the interior thereof, and a check valve in each of said pipes.

2. In combination with an internal combustion engine having an exhaust duct and a carburetor, a source of fuel supply, a pumping bottle partly seated in said duct, a pipe connecting said source of supply to said bottle, a check valve in said pipe, a storage tank arranged above said carburetor, a pipe connecting said bottle to said tank, an overflow pipe connecting said tank to the source of supply, and a pipe connecting said tank and carburetor.

3. Apparatus of the character described including, a thermal pump comprising a vessel closed at one end, a second vessel closed at one end and arranged within the first with its closed end adjacent to but spaced from the closed end of the first vessel and having its outer periphery spaced from the inner periphery of the first named vessel to form a restricted space therein, said second vessel having ports adjacent its closed end communicating with said restricted space.

4. In combination with an internal combustion engine having an exhaust manifold, main and auxiliary tanks arranged at different elevations, a thermal pump including a tubular shell carried by the manifold and subjected to the heat of the exhaust gases passing therethrough, said pump being constructed to provide a vapor chamber and having intake and discharge pipes communicating respectively with the main and auxiliary tanks, and check valves arranged in said pipes.

5. A fuel pumping system for an internal combustion engine comprising, in combination with the exhaust pipe of the engine, an open fuel supply tank, a thermally operated pump having a chamber disposed in part within said exhaust pipe, a feed pipe lead-

ing from the fuel supply tank to the pumping chamber, a check valve in said pipe, a discharge pipe also communicating with said chamber, a check valve in said discharge line, a reservoir for receiving liquid discharged by said discharge line, a feed connection from said reservoir to the carburetor of the engine, and an overflow pipe leading from the reservoir to the supply tank.

6. The method of feeding liquid fuel to a heat generating fuel burner which comprises, subdividing a mass or body of liquid fuel into successive small charges, taking heat from the burner and adding the same to each charge in succession, vaporizing a portion of each charge by said added heat, performing the mechanical work of moving successive charges to the burner by the expansion of said vapor of each charge, condensing the vapor of each charge by absorbing the heat of vaporization in the succeeding charge, and employing the heat remaining in each charge to assist in vaporization of the fuel fed to the burner.

7. In combination with an internal combustion engine having a carburetor and exhaust pipe, a fuel tank, a reservoir for feeding the carburetor, a heat operated pumping device connected between the tank and the reservoir, a connection from the exhaust pipe to said pumping device to supply heat thereto from the exhaust gases of the engine, and means controlled by filling of the reservoir for stopping the effective pumping of the fuel.

8. The combination with an internal combustion engine having a carburetor and an exhaust pipe, of a fuel tank, a reservoir for feeding the carburetor, a heat operated pumping device connected between the tank and the reservoir, a connection from the exhaust pipe to said pumping device to convey a portion of the exhaust gases of the engine thereto, and level controlled means for stopping the effective pumping of fuel when the reservoir is full.

9. In a fuel feeding system for internal combustion engines, the combination of an engine having a carburetor and an exhaust pipe, a low level fuel supply tank, a feed line from the bottom of the tank to the carburetor, a thermal pumping element in series relation in said feed line at a point where it will be filled by gravity from said tank, and means to heat the pumping element from the exhaust pipe of the engine.

10. In combination, an internal combustion engine, a fuel feeding device therefor, a fuel supply tank, a pumping chamber having an inlet communicating with said supply tank and an outlet communicating with said fuel feeding means, means for heating said pumping chamber from the exhaust gases from said engine, and means associated with said chamber whereby the heat-

ing of the liquid therein creates pumping pulsations in said chamber.

11. The herein described method of preparing fuel for use in an internal combustion engine which comprises utilizing the waste heat of said engine for vaporizing small volumes of fuel intermittently, utilizing the pressure of the vapor to set up a circulation of heated fuel, and drawing from this circulating volume of heated fuel as required.

12. A fuel supply system for internal combustion engines including in combination with the exhaust pipe of an engine, main and auxiliary tanks arranged at different elevations, and a thermal pumping device carried by the pipe and subjected to the heat of gases passing therethrough and having pipes communicating respectively with the

main and auxiliary tanks and reversely operating valves in said latter pipes.

13. A fuel supply system for internal combustion engines including in combination with the exhaust pipe of an engine, main and auxiliary tanks arranged at different elevations, and a thermal pump device carried by the exhaust pipe and subjected to the heat of exhaust gases passing therethrough, said pump device being constructed to provide a vapor chamber and having intake and discharge connections respectively communicating with the main and auxiliary tanks, and reversely operating check valves arranged in said intake and discharge connections.

In testimony whereof I have signed my name to this specification.

LESTER E. VAN HISE
